UNITED STATES PATENT OFFICE

1,924,213

STEPLADDER

William P. Newman, Bucyrus, Ohio

Application October 17, 1929. Serial No. 400,237

1 Claim. (Cl. 228—31)

This invention relates to improvements in step ladders.

It is well known to users of step ladders of the conventional type, that it is very dangerous to use such step ladders at different places and for different purposes when climbing the steps, especially to the higher steps thereof and that walking of the ladder is incident to its use, and that it tends to vibrate, shake and tremble when in use, tipping or falling at times in lateral directions.

One of the objects of the invention is to provide lateral brace supports on the step ladder to counteract the tendency of same to vibrate and fall in lateral directions to prevent same from falling and to provide means whereby its rear braces, ladder and the auxiliary lateral brace supports are all linked together, so that the person who spreads the ladder for use can impart simultaneous outward movement to all of the parts preparatory to using the ladder and inward movement for collapsing the links for folding in compact form for storage or the like.

A further object of the invention is to provide means for holding the link bar connections at one end below their connections to the step ladder and auxiliary parts thereof, when the ladder and auxiliary parts are set up and spread for use.

Another object of the present invention is to provide means for linking all movable parts of the ladder together by a simple, durable, and efficient mechanism which links all the movable brace supports and the movable parts of the ladder to provide means for imparting movement to all simultaneously, when any movable part of the ladder is manipulated for the purpose of spreading it for use or folding it for any purpose.

A further object of the invention is to provide means for speedily, conveniently and simultaneously folding the parts of the ladder together for storage or spreading the parts of the ladder for use, without assembling any of the parts of the ladder by the use of tools.

I attain these and other objects by the mechanism illustrated in the accompanying drawing, in which—

Figure 1 is a side elevation of a step ladder, showing my invention applied thereto, and in position for use.

Figure 2 is a front elevation of a step ladder, showing my invention applied thereto, in full lines, when the step ladder is in use, and the invention or controlling means of the parts in dotted lines when the controlling means is in its folded position.

Figure 3 is a plan view of the invention or con-

trolling means, showing the link bars pivotally attached to movable parts of the ladder for imparting movement thereto taken on the line 1—1 of Figure 1.

In the drawing, the step member of a conventional type of step ladder is indicated by the side members 1 and 2 and the steps 3.

Rear braces 4 and 4' are pivotally attached to the step member by brackets 5, pivoted on pins 6. Bifurcated or ear portions 7 are provided on the sides of brackets 5, and lateral brace supports 8 are inserted between the bifurcated portions and they are pivotally connected thereto by pins 9 which provide means for swinging the lateral brace supports toward and away from the sides 70 of the ladder.

It will be noted that when the lateral brace supports are positioned in the position shown in Figure 2, that the ladder is prevented from having a tendency to fall in lateral directions or to tremble, shiver, or walk, as is incident to the use of a conventional type of step ladder. The step ladder stands firmly on all supports or legs and its liability to vibrate and tremble, or walk, and its lack of equilibrium are counteracted when in use by the lateral brace supports attached to swing toward and from the sides of the ladder.

No invention is claimed for the above described parts except in combination as they are well known in the prior art.

It has been found that in order to get the said beneficial results with convenience and efficiency to the user of the step ladder, that a means for controlling the movable parts of the step ladder simultaneously, from any movable part of the step ladder must be employed to move the parts in unison for use for folding or spreading same when not in use. The controlling means for performing these results is constructed to operate in combination with the step ladder parts and lateral brace supports. The controlling means is constructed and applied to the parts of a conventional step ladder as follows:

Link brace bars 10 and 11 are provided and one of their ends are bent at 12 and 13 and pivotally attached to the side members 1 and 2 of the step ladder, by pins 14 and 15. Their opposite ends are bent at 16 and 17 and are adapted to contact with each other and are held in place by portions of angular members 19 and 20. They are pivotally held in place through the medium of a pin 21. In opposed relation, thereto, similar braces 22 and 23 are provided and pivotally attached to the brace members 4 of the step ladder, by pins 24 and 25 and pivotally held in place 110

by portions of the angular members 26 and 27 by a pin 28.

It will be observed that the said construction provides means for spreading the step member 5 and rear brace members 4, or folding them together as desired by the operator.

To the other portions of angular members 19, 20, 26 and 27, straight link brace bar members 29 and 30 are pivotally attached by pins 31 and 32. 10 The opposite ends of the bars 29 and 30 are pivotally attached, by pins 33 and 34, to the lateral brace supports 8.

It will be noted that the link brace bars are attached to all movable parts of the step ladder 15 and lateral brace supports thereof, so that, if one of the parts is moved simultaneously therewith, each other movable part is moved at once to spread all of the parts of the step ladder parts and lateral brace supports for use or to fold same 20 together. All of the link brace bars are pivotally connected at a central point at one end and their opposite ends are bent to aline for pivotal movement and are attached to pre-determined movable parts and braces of the step ladder.

25 Attention is directed to Fig. 2 of the drawing. It will be noted that in this figure, the position of the controlling means as indicated by reference numeral 35 in full lines which is the position of the ladder and its auxiliary lateral brace supports 30 assume, when the step ladder is used. The folded position of the controlling means is indicated by reference numeral 36 as indicated in dotted lines, when not in use. The folded position of the lateral braces are also indicated in dotted lines 35 in said figure.

When it is desired to use the step ladder, movement is imparted to any movable part of the step ladder by pressure which is exerted thereon, and all of the movable members are then moved 40 together simultaneously to the full line of position as indicated in 35 of Fig. 2. When it is desired to fold the step ladder for any purpose, the operation is reversed and a controlling means as herein described, is moved to the dotted line position as shown in 36 in Fig. 2.

It will be noted as shown in Fig. 1, that the connections of the link brace bars depend below 45 their connections or axis to the movable parts of the step ladder, or in other words depend below the horizontal center thereof, to prevent same from moving upward. They are prevented from moving downward by a stop as indicated in 37 which provides a support for the bars 10 and 11, and which hold same in position for use. This 50 stop is in the form of an L-shaped bracket hav-

ing the upright portion secured to an upright of the step member of the ladder, and the outstanding portion or horizontal leg underlying the link 11 of the connection to receive and limit downward movement of the link to maintain the center bracket below the center, all as clearly shown in Fig. 2. If desired, a shelf can be secured to the step ladder, as indicated in 38, and pivoted to the braces 4 in the usual manner. The shelf, however, is unnecessary unless desired for some specific reason.

The construction and operation of the controlling means for parts of the step ladder and auxiliary parts as described, provide a convenient, safe, efficient and speedy means for simultaneously folding the movable parts of the step ladder and auxiliary parts together for storage or the like, or for spreading same for use when desired. Operation of the step ladder and its auxiliary parts can be performed from any position around the step ladder by pressure on any one of the movable parts of the step ladder or its auxiliary parts or braces to prepare it for use, or folding it for any purpose.

I claim:

A step ladder comprising a step member including uprights, a bracing member including uprights, lateral brace members swingingly connected to the upper end of the step ladder for lateral bracing of the step ladder in both directions, a center bracket made up of four right-angled sections arranged to present spaced bars extending toward the respective parts of the ladder, a pair of links pivotally connected between each set of spaced bars projecting toward the step member and bracing members, the links of each pair diverging beyond the center member and being pivotally connected terminally to the uprights of the step member and bracing member respectively, a single link pivotally connected between the bars of the center member and projecting toward and connected to the lateral braces, and an L-shaped stop member having the upright thereof connected to one of the uprights of the step member and the lateral portion thereof in position to underlie and receive one of the links connected to the step member to limit downward movement of such link and thereby position all links at a downward inclination when the parts of the step ladder are in operative position to thus arrange the center bracket below the pivotal connection of the links with the ladder parts.
